CLEANING ARTICLE

Mitchell Carter, Trenton, N. J., assignor to The Firestone Tire & Rubber Company, Akron, Ohio, a corporation of Ohio

Application December 19, 1946, Serial No. 370,792

1 Claim. (Cl. 15—244)

The present invention relates to cleaning articles generally, especially to cleaners used for scrubbing or cleaning greasy or extremely dirty articles.

Heretofore greasy, or very dirty articles, such as pots and pans, have been cleaned by the use of copper or steel wool scrubbing articles, a great variety of which are upon the market today. However, all such articles are open to the objection that they do not retain soap and water therein so that the entire cleaning action is due to the abrasive action of the metallic wool. If soap or water is to be used in cleaning the article, then an ordinary rag or brush is used to remove the dirt or grease from the article. No cleaning article upon the market today has effectively combined an abrasive cleaning action with the use of an emulsifying or cleaning agent, such as soap.

The general object of the present invention is to provide an improved cleaning article which is adapted to combine both an abrasive and an emulsifying cleaning action on the article to be cleaned.

A further object of the present invention is to provide a tough but resilient cleaning article which has a long life.

A further object of the invention is to provide a novel cleaning article from cellular rubber and abrasive material.

The foregoing and other objects will be manifest from the accompanying specification, reference being had to the accompanying drawing of which:

Figure 1 is a transverse section of a cleaning article embodying the invention, and a mold in which the articles are formed: and

Figures 2 and 3 are fragmentary detail sectional views, on a larger scale, of other embodiments of the invention.

In the drawing, a cleaner or cleaning article 10 is shown, which article mainly comprises cellular rubber 11, which has intercommunicating cells and preferably is made directly from latex by beating and/or aerating same to form cellular rubber therefrom in accordance with well known practice. The cellular rubber 11 may be provided with a base 12 and with a base flange 13. A dense rubber skin 14 extends over the sides and base of the cellular rubber body 11. The cleaning article 10 also includes a mass of stainless steel wool 15 which is embedded in the cellular rubber 11 and which is made from a very soft, or annealed stainless steel. The stainless steel wool

is used to provide the article 10 with an abrasive material for removing grease or large particles of dirt from an article to be cleaned. The cleaning action of the abrasive, stainless steel wool, is aided by soap and water which ordinarily will be used in conjunction with the cleaning article and which will be carried in the cellular rubber. Hence, two types of a cleaning action are combined by the use of the cleaning article of the invention, whereas such combination has not been possible when using types of cleaners heretofore available.

The article 10 is made in a suitable mold 16, the molding cavity of which is first provided with a layer or skin of rubber, or rubber-like substance by pouring a dispersion of such substance into the mold and depositing a layer on the mold surface. The excess dispersion is then removed from the mold and stainless steel wool, which may be formed to substantially the shape desired, is introduced into the mold. Then before the gel of rubber, or rubber like material is completely set up, aerated latex is poured into the mold and it flows around and fills up the space between the particles of stainless steel wool. Lastly the latex is gelled and vulcanized to produce the finished article in which the particles, or fibers of stainless steel wool are bound together by the cellular rubber. The rubber 11 can be given maximum strength by thoroughly drying it before vulcanization is effected, and the rubber skin 14 may be formed in accordance with the disclosure in my copending application Serial No. 370,791, filed December 19, 1946.

A modified cleaning article 10a, substantially the same as the article 10, is shown in Figure 2. The article 10a has an impervious skin 14a thereon formed around a cellular rubber core 11a and has stainless steel wool 15a embedded therein. The cleaning action of the article 10a is enhanced by abrasive particles 17, such as pumice, which are embedded therein. The abrasive particles should be compounded in with the latex used in forming the cellular rubber 11a and in all events, are distributed through the cellular rubber to provide a somewhat different cleaning action from that obtained solely by use of stainless steel wool. A cleaning article 10b, which has no impervious surface skin thereon but which otherwise is identical with the cleaning article 10, is shown in Figure 3, which cleaning article may be most suitable for some purposes. In a further modification of the invention, a cleaner may be made solely from cellular rubber which

has an impervious skin over a portion of the cleaner.

It will be seen that a cleaning article having a waterproof yet flexible covering over most of its surface is provided by the invention. Hence, the cleaner can be used by a person without getting the user's hands wet. Also, the soap or other cleaning agent is only applied to one surface of the article whereby a savings is effected. Use of an oil and grease resistant rubber is especially desirable where the article is to be used in cleaning oily or greasy surfaces. The edges of the skins on the cleaning articles, as the center portions of such articles wear away in use, can be cut down by a pair of shears. Obviously the cleaning article may have any desired shape.

From the foregoing, it will be seen that a novel cleaner has been provided by the invention and the objects of the invention have been achieved.

While several embodiments of the invention

have been completely illustrated and described herein, it will be appreciated that further modifications thereof may be made without departing from the scope of the invention as defined in the appended claim.

5 What is claimed is:

A scrubbing cleaning article comprising a body of intercommunicating cellular rubber, and abrasive means comprising a mass of soft, annealed stainless steel wool embedded in and extending through said body to reinforce the same and enhance the cleansing action thereof, the body having a base portion, side portions and an exposed end portion, an impervious skin of a flexible material bonded to said base portion and side portions, and said body having a base flange, whereby the article is adapted to be held comfortably in the hand of a user.
